UNITED STATES PATENT OFFICE.

MATTHEW F. BAYER, OF KENOSHA, WISCONSIN, ASSIGNOR TO SIMMONS COMPANY, OF KENOSHA, WISCONSIN, A CORPORATION OF DELAWARE.

WALL BED.

Application filed September 15, 1924. Serial No. 737,661.

My invention relates to improvements in wall-beds. It is of particular service in connection with that type of up-ending wall-bed which may be mounted on a swinging frame, which may be rotated on a vertical axis to conceal the bed either behind a door or elsewhere.

The principal objects of the invention are to provide a bedstead of the class described which may be folded into small compass so that the storage space required is relatively small; to provide a bed of the class described which may be conveniently swung on a vertical axis when folded or unfolded; to provide a construction the manipulation of which is exceedingly simple and requires a minimum of effort in its manipulation; to provide a construction which, while being easy to operate will be safe against accidental folding when in use as a bed; to provide a structure which will securely retain its folded position when folded; to provide a construction which shall be neat in appearance, rugged and durable, simple in design, economical to manufacture and trouble-free, and in general, to provide an improved wall bedstead of the character referred to.

In the drawings which illustrate my invention as applied to a wall-bed adapted to swing through the door of a closet,

Fig. 1 is a side elevation of the structure showing the bedstead extended or unfolded.

Fig. 2 is a view similar to Fig. 1 showing the bedstead upended preparatory to swinging the same through the doorway of the closet.

Fig. 3 is a section taken on the line 3—3 of Fig. 1.

Fig. 4 is a fragmentary end elevation of the bedstead looking from the right hand of Fig. 1.

Fig. 5 is a section taken on the line 5—5 of Fig. 1.

Fig. 6 is a section taken on the line 6—6 of Fig. 1.

Fig. 7 is a section taken through the line 7—7 of Fig. 3, and

Fig. 8 is a section taken on the line 8—8 of Fig. 1.

Referring to the drawings, 10 represents a portion of the jamb of the doorway through which the bedstead with its supporting structure is adapted to swing. Said swinging connection is in the present instance afforded through the medium of a

tubular standard 11, to which the structure is secured, and which standard is supported at its upper end by a bracket 12, and at its lower end by a pedestal 13. As shown best in Fig. 7, the pedestal 13 comprises a casting which is bolted to the floor of the room, said pedestal having a boss 14 bored out to rotatably receive the reduced end 15 of a pivot stud 16 fitting the interior of the tubular standard 11 and secured therein by means of a transverse, diametric pin 17. The pivotal connection of the upper end of the tubular standard 11 is effected by securing in the upper end of said standard a pivot stud 18, having an upper reduced extension 19 rotatable in the projecting lug 20 formed as a part of the bracket 21. Said bracket 21 is secured to the jamb 10 by means of suitable wood screws as at 22.

There is looped around the upper end of the standard 11 a length of angle iron, the horizontal flange of which is cut away so that it will fit the standard 11, as indicated in Fig. 5. Adjacent the standard, the uncut portions of the said flange are connected together by riveting thereto a short strap member 23. The outer ends of the vertical flanges 24 of said angle iron are bent in opposite directions, as indicated at 25 and 26, said bent portions being bolted or riveted to the vertical flange of a length of angle iron 27 extending horizontally and perpendicular to the upper standard arm 28 just described.

The horizontal flanges of the arm and the angle iron 27 are also supplementarily secured together by means of rivets as at 29. A pin 30 extending diametrically through the standard and portions of the flanges 24 of the arm 28 serve to lock said arm rigidly to the upper end of the standard.

A lower arm 31 similar in construction to the arm 28 is secured to the lower end of the standard 11 by means of the diametric pin 17 previously described, the outer end of said arm 31 being similarly secured to a length of angle iron 32 below the angle iron 27 and parallel thereto. The angle irons 27 and 32 are suitably secured as by bolts 33 to somewhat larger and longer similarly extending angle iron bars 34 and 35, which parts 34 and 35 constitute transverse members or cross bars of a rectangular frame structure, the vertical members of which are designated 36 and 37.

To the verticals 36 and 37 there are secured, for example, by means of bolts 38 (see Fig. 5), the post members 39 and 40 of an ornamental head frame shown best in Fig. 3, said head frame moving with and constituting a part of the swinging, supporting structure. To the lower ends of the verticals 36 and 37, there are secured, for example, by means of bolts 41, a pair of outwardly extending substantially horizontal angle bars 42 which may conveniently be made of a single piece of angle iron, the intermediate portion of which constitutes a connecting cross bar 43, for the outer end 10 of said extensions 42. As shown, the extensions 42 are spaced slightly from the floor surface 44 so as not to interfere with the swinging of the main structure around the axis of the standard 11. The outer ends of 15 said bars 42 are maintained in vertical position by means of diagonal brace bars 45, the ends of which are suitably secured to the verticals and the extensions respectively.

The bolt 46 constituting the securing 25 means for the lower ends of the brace bar 45 also forms a pivot for the lower end of a swinging outer link 47, which swinging link, as shown in Figs. 1 and 2, is substantially vertical when the bedstead is in either of its 30 two extreme positions. The inner link 48 is pivoted at its lower end on a pivot 49, fixed in the end of the bar 42 adjacent the junction of said bar 42 with the vertical frame member 36.

The principal supporting elements of the bedstead proper designated as a whole 50, comprise a pair of side longitudinals 51 preferably tubular. Each of said tubular side bars 51 carries at its ends, risers 52-53 35 of any desired form but preferably constructed of forged angle iron. To the outer ends of said risers 53 there is secured an angle iron cross bar 54 to which one end of the bed fabric 55 is connected through the medium of helicals 56. To said cross bar 45 45 there is also secured a bail shaped rod 57 which constitutes a stop for the inner end of the mattress 58.

To the outer end of the risers 52 there is 50 similarly secured a cross bar 59 to which the outer end of the bed fabric 55 is similarly connected. Also, to said cross rail 59 there are secured a pair of bedding clamps 60 of a construction well known to those skilled in 55 the art. The risers 52 also serve as supports for plates 61 secured thereto, said plates being fastened to the inner side of the vertical post members 62 of the ornamental foot end frame designated as a whole 63. As is usual 60 with bedsteads of this up-ending type, the legs of the outer end of the bedstead are adapted to fold as indicated at 64 in Fig. 2. Said folding connection comprises a slotted filler member 65 secured in the upper end 65 of the folding leg 64 by the pin 66. The

slotted end of said filler 65 is arranged to slide up into the hollow lower end of the vertical post member 62 as indicated in Fig. 1, a transverse pin 67 serving to limit said sliding movement when the outer end of the bedstead is elevated.

There are provided as an important feature of the construction, a series of balancing or assisting springs, such springs which are of the helically coiled wire tension type 75 having their lower ends hooked into apertures punched in the vertical flange of a cross angle 68 secured to the lower extension bars 42 of the supporting frame at points intermediate the pivots 46 and 49. The upper ends of said helicals 69 are hooked into apertures punched in the upper flange of an angle iron cross bar 70, secured to the side bars 51 of the bedstead, by means of an intermediate angle-iron 71 riveted to the upper surfaces of said side bars 51.

As shown best in Fig. 1, the upper ends of the helicals 69 are thus connected to the bedstead at a point located a substantial distance above the center line of the side bars 51, through which center line passes the axes of the pivots 72 and 73 of the upper ends of links 48 and 47. The construction of said pivot connection 72 and 73 is best shown in Figs. 5 and 8, and it will be 95 also observed by reference to Fig. 1, that the upper ends of the springs 69 occupy a position intermediate the pivots 72 and 73, in the present instance slightly closer to the pivot 72.

The dimensions of the various parts are such that when the bedstead occupies the position in Fig. 1, there is a slight tendency for the springs 69 to elevate the outer end of the bedstead, but because of the fact 101 that the pivot 72 of the inner link 48 is comparatively close to a vertical plane passing through the lower pivot 46, this lifting tendency is relatively insignificant, and as a matter of fact it is impossible to tip the 110 bedstead upwardly by loading the inner end thereof. However, when the outer end of the bedstead is lifted to fold the same the pivot 72 rapidly swings outwardly as 115 shown by the dotted lines in Fig. 2, so that by the time the end of the bedstead attains an elevation, such that it is difficult to manage without considerable assistance, the lifting tendency of the springs has been increased to a point where it will substantially 120 balance the weight of the structure. The dotted line position in Fig. 2 indicates approximately the position of equilibrium. When the bedstead is further elevated the 125 center of gravity of same finally moves inwardly of a vertical plane passing through the upper pivot 73 of the outer link 47, and hence in the full line position shown in Fig. 2, the bedstead will maintain itself securely in folded position, even though in 130

such position the springs 69 are completely relaxed. However, in order to prevent the springs from unhooking, I prefer to make them of such length that there is a very slight pulling tendency, even when the bedstead has attained the vertical position shown in Fig. 2.

Since the described details of construction and operation are illustrative of merely a single embodiment of my invention, the scope of same should be determined by reference to the appended claims, said claims being construed as broadly as possible consistent with the state of the art.

15 I claim as my invention:

1. An up-ending bedstead construction comprising a supporting frame, a bedstead tiltable on said frame, an inner and an outer swinging link pivotally mounted on said frame with axes of rotation at substantially the same height, and spaced horizontally, the swinging ends of said links being pivotally connected to said bedstead at points above said axes, and spaced apart 20 a distance less than the spacing of the axes, an assisting tension spring, one end of which is connected to said support intermediate said axes, the other end of said spring being connected to the bedstead intermediate the link pivots.

2. An up-ending bedstead construction comprising a supporting frame, a bedstead tiltable on said frame, an inner and an

outer swinging link pivotally mounted on said frame with axes of rotation at substantially the same height, and spaced horizontally, the swinging ends of said links being pivotally connected to said bedstead at points above said axes, and spaced apart 25 a distance less than the spacing of the axes, an assisting tension spring, one end of which is connected to said support intermediate said axes, the other end of said spring being connected to the bedstead intermediate the link pivots, at a point located 40 always inwardly of the outer link.

3. An up-ending bedstead construction comprising a supporting frame, a bedstead tiltable on said frame, an inner and an outer swinging link pivotally mounted on said frame with axes of rotation at substantially 50 the same height, and spaced horizontally, the swinging ends of said links being pivotally connected to said bedstead at points above said axes, and spaced apart a distance less than the spacing of the axes, an assisting tension spring, one end of which is connected to said support intermediate said axes, the other end of said spring being connected to the bedstead intermediate the link pivots, 55 at a point located always inwardly of the outer link, the outer link being substantially vertical when the bedstead is in both of its extreme positions.
